UNITED STATES PATENT OFFICE.

ANTON OHNEMUS, OF QUINCY, ILLINOIS, ASSIGNOR TO THE EXCELSIOR STOVE AND MANUFACTURING COMPANY, OF SAME PLACE.

DESIGN FOR A DOOR.

SPECIFICATION forming part of Design No. 32,069, dated January 2, 1900.

Application filed October 26, 1899. Serial No. 734,890. Term of patent 7 years.

To all whom it may concern:

Be it known that I, ANTON OHNEMUS, a citizen of the United States, residing at Quincy, in the county of Adams and State of Illinois, have invented and produced a certain new and original Design for Doors, of which the following is a specification, reference being had to the accompanying drawing, forming part thereof.

The drawing is a perspective view showing my design.

As shown in the drawing, the leading or material feature of my design consists in a

door having an upper face A and lower face B, divided on a line C by a lip-shaped ledge D. Extending approximately the length of the door is a T-shaped swell formed with a lip-shaped cross-bar F and with body parts E and G, divided by a rib H.

I claim as my invention—

The design for a door; substantially as herein shown and described.

ANTON OHNEMUS.

In presence of—

JOHN J. FISHER,
THEO. EKEHART.
